(No Model.)

J. MATHIESON.
SHUTTLE BOX MECHANISM FOR LOOMS.

No. 404,640.

Patented June 4, 1889.

UNITED STATES PATENT OFFICE.

JOHN MATHIESON, OF GLASGOW, COUNTY OF LANARK, SCOTLAND.

SHUTTLE-BOX MECHANISM FOR LOOMS.

SPECIFICATION forming part of Letters Patent No. 404,640, dated June 4, 1889.

Application filed November 8, 1887. Serial No. 254,662. (No model.) Patented in England April 14, 1887, No. 5,407, and in France July 9, 1888, No. 184,708.

To all whom it may concern:

Be it known that I, JOHN MATHIESON, over-
looker, a subjeet of the Queen of Great Brit-
ain and Ireland, residing at Bell Street, Cal-
ton, in the city of Glasgow, county of Lanark,
North Britain, have invented certain Im-
provements in Shuttle-Box Mechanism for
Looms for Weaving, (for which I have ob-
tained patents in Great Britain, No. 5,407,
dated April 14, 1887, and in France, No.
184,708, dated July 9, 1888,) of which the fol-
lowing is a specification.

My invention relates to mechanism em-
ployed to control the movements of the drop-
boxes in looms which are adapted to change
the shuttles during the weaving process, as is
well understood. In such looms the several
shuttles are contained in boxes, which are
raised or lowered as may be required to bring
any particular shuttle into use, and to effect
this raising and lowering with certainty and
correctness and without shock or violent ac-
tion is the object of my invention. I connect
the drop-box with a rocking lever, which can
be moved upon its fulcrum into any one of sev-
eral positions corresponding to the number
of shuttles, the said movement being regu-
lated by means of vibrating levers or arms,
which act upon the said lever to move it into
the required position, each arm being adapted
to move the lever into a different position.
Each arm is provided with a hinged hook,
which is connected with a suitable pattern
chain or barrel or pattern mechanism, which
governs the action of the parts. A bar or rod
is caused to reciprocate, or is carried by an
arm or by arms or by a vibrating frame which
is acted upon by a crank or tappet. As the said
bar or rod vibrates, one or another of the said
hinged hooks is moved into position by the ac-
tion of the pattern mechanism to engage with
the said bar or rod for each change of the
shuttle, the consequence being that the con-
nected arm will be caused to move upon its
fulcrum and thereby to act upon the drop-
box lever.

In the accompanying drawings, Figure 1 is
an elevation of the parts of the new motion
as they appear when looking toward the end
50 of the loom. Fig. 2 is an elevation of the parts

as they appear when looking toward the front
of the loom.

As the loom itself may be of any ordinary
or suitable construction, no part of the loom
appears excepting the parts which are immedi- 55
ately connected with the new motion.

In the drawings, *a* is the said vibrating
lever. *b'* to *b⁴* are the said arms, four in num-
ber, and *A* is the drop-box.

The lever *a* is mounted upon a fulcrum at *c*, 60
and one end of the lever is connected by a
link *d* with the drop-box. The other end of
the lever is formed with a curved face *a'*,
upon which bowls 1 to 4, carried by the vi-
brating arms *b'* *b⁴*, act to move the lever. These 65
bowls differ in distance from the common
fulcrum *e* of the arms, so that each arm has a
different action upon the lever. To each arm
b is hinged a hook *f*, which is connected by
means of a rod or wire *g* with a lever *h*, there 70
being four of these levers, one for each hook.
These levers are mounted upon a fulcrum at
i, and each is provided with a pin *j*.

The barrel of the pattern-chain *k* is carried
by a lever-frame *l*, which has a lever-arm *l'*, 75
which is connected by a link *m* with a crank
n upon the tappet-shaft, the effect being that
the pattern-chain barrel is moved toward and
from the pins *j*. Any pin which has not pre-
sented to it a hole in the pattern-chain is 80
pushed upward by the movement of the pat-
tern-chain barrel, the effect being that the
corresponding lever *h* is moved upon its ful-
crum and the connected hook *f* is drawn in a
direction toward the right hand in Fig. 1. A 85
lifting-bar *o* is carried by arms *o'*, which are
mounted to vibrate upon an axis at *e*, which
is also the fulcrum of movement of the arms
b, as aforesaid. The said lifting-bar *o* is con-
nected by a link *p* with a crank upon the tap- 90
pet-shaft. In the example the crank *n*, which
actuates the arm *l'*, also actuates the lifting-
bar. As this bar vibrates, any one of the
hooks *f* which is drawn to the right hand, as
aforesaid, is caught by the lifting-bar and is 95
lifted thereby, as in the case of the hook
marked *f'*, the result being that the connected
arm is moved from the position of the arm *b'*
to the position of the arm marked *b⁴*. The
bowl upon this arm is at the greatest distance 100

from the fulcrum e , and determines the position for the lever to move the drop-box to its highest position or to keep it in such position. A spring q acts upon the lever a and tends to raise the drop-box. A curved face a^2 is formed upon the lever a , and is concentric with the axis c of the lever. A brake r , fixed upon a shaft r' , is kept pressed against this curved face by the action of a cam s , which is fixed upon the tappet-shaft. This cam, by depressing and holding down the end of a spring-lever t , which is attached to the brake-shaft r' , keeps the brake pressed upon the face a^2 during the revolution of the cam, excepting at the time when the lifter-bar is in its highest position, as indicated in the drawings. At such times a flat upon the cam relieves the pressure upon the brake-lever, and the lever a is then free to yield to the action of the spring if not prevented from so yielding by one of the bowls upon the arms b . When the parts are in the positions represented in Fig. 1 the lever is prevented from moving by the bowl 4.

To render the action more clear I will number the bowls on the arms b 1, 2, 3, and 4. On the lifter-bar o moving downward the bar b^4 would be released and fall back into the position of the bar b' . Supposing the arm carrying the bowl 1 to be next lifted, the lever would be moved to the full extent of its range of motion and the drop-box would be lowered to its lowest point. So long as the said arm continued to be lifted the drop-box would be stationary; but supposing the arm carrying the bowl 2 to be lifted, the brake r at the same time being eased, the spring would be free to move the lever until the said bowl stopped the movement, and the drop-box would fall one step, or into position to bring the second shuttle into action. If the arm carrying bowl 3 had been lifted, the drop-box would have fallen two steps to bring the third shuttle into action, and so on, the drop-box being either lowered by the action of the bowls or raised by the action of the spring into positions governed by the bowls. The studs carrying the bowls are adjustable in slots formed in the arms, as indicated in the drawings.

Although I prefer to use bowls or rollers revolving upon studs fixed to the arms, in order to reduce friction, such bowls are not absolutely necessary. In the example the connecting-link p is of a peculiar formation, be-

ing adapted to release its hold upon the lifter-bar in the event of an obstruction to the movement--such, for example, as would be caused by the jamming of a shuttle in the shuttle-box. A stud or projection at u is fixed to or formed in the said frame o' in line with the bar o , and is gripped between two jaws $p\ p'$, which are formed by the hinging of a part p to the link p . The two jaws are drawn together like a pair of nipper-tongs by means of a spring v , which is of sufficient power to enable the link to perform its ordinary work. In the event of an excessive strain the jaws open and release the stud, so as to prevent the breakage of any of the parts.

I do not confine myself to the exact formation of the lever a , so long as it is adapted to be acted upon by the arms b to raise or draw downward the drop-box.

Having fully described my invention, I would state that what I claim is—

1. In a loom drop-box motion, the lever a , the operating-spring, and the drop-box connected to the lever, in combination with vibrating arms provided with hooks, pattern mechanism controlling the hooks, a lifter for the hooks, and mechanism to operate the lifter, all substantially as set forth.

2. In a loom drop-box motion, the lever a , the drop-box, a spring to raise the drop-box, a brake to hold the lever, a holding or releasing cam or tappet controlling the brake, and the arms vibrating to raise one arm of the lever a , and thereby to lower the drop-box, in combination with hooks on the vibrating levers, pattern mechanism acting on the hooks, a lifter-bar, and means for operating the latter, all substantially as described.

3. The drop-box, the lever a controlling the drop-box, vibrating arms of varying length to rock the said lever on its fulcrum in one direction, and a spring to move the lever in the other direction, in combination with pattern mechanism for selecting the arms to be vibrated and with hooks connected to the arms, a vibrating lifter-bar, and mechanism to operate the latter, all substantially as set forth.

In testimony whereof I have signed my name to this specification in the presence of two subscribing witnesses.

JOHN MATHIESON.
